UNITED STATES PATENT OFFICE.

HERBERT McCORNACK, OF BLOOMFIELD, NEW JERSEY, ASSIGNOR TO EMPIRE CREAM SEPARATOR COMPANY, OF BLOOMFIELD, NEW JERSEY, A CORPORATION OF NEW JERSEY.

PULSATING MECHANISM.

1,392,346.

Specification of Letters Patent.

Patented Oct. 4, 1921.

Application filed July 2, 1917. Serial No. 178,078.

To all whom it may concern:

Be it known that I, HERBERT McCORNACK, a citizen of the United States, residing at Bloomfield, county of Essex, and State of 5 New Jersey, have invented certain new and useful Improvements in Pulsating Mechanism, of which the following is a specification.

This invention relates to mechanism actuated by inequalities in fluid pressure for 10 producing a pulsating, intermittent or reciprocating action and particularly to mechanism of this character adapted for use in cow milking machinery.

15 Among the objects of the present invention are to provide a mechanism of this character which shall be certain and regular in operation, which may be readily adjusted as to rate and character of pulsations 20 produced, which shall be durable, which may be easily taken apart for cleaning or repair and which may be manufactured at a moderate cost. In connection with cow milking machinery particularly, an attainment 25 of these objects is of the utmost importance. Certainty and regularity of operation are necessary in order to avoid the danger of injury to the cow. Durability is also of the highest importance owing to the 30 conditions of use of such machines on farms or dairies, often in remote localities where expert services for repair and new parts for replacement are difficult to obtain. Adjustability to suit the requirements of particular 35 cases is also most desirable.

The invention also contemplates certain 40 improvements in puppet valve and check valve constructions and other features as will fully appear from the following description.

In the accompanying drawings, which form a part of this specification and in which are illustrated certain preferred embodiments of the invention, Figure 1 is a 45 side elevation of a milking unit showing a form of the invention applied thereto. Fig. 2 is a vertical sectional view through the pulsator mechanism showing the parts in what may be referred to as the "first" position in the cycle of operation. Fig. 3 is a 50 similar view showing a "second" or intermediate position of the parts. Fig. 4 shows the "third" or final position of the parts before they return to the position shown in 55 Fig. 2. Fig. 5 is a horizontal sectional

view of the mechanism taken on line V—V of Fig. 4. Fig. 6 is a detail view of the handle shown in Fig. 1. Fig. 7 is a plan view of the adjustable air inlet cap. Figs. 8 and 9 are vertical sectional views illustrating a modified construction and showing moving parts at the lower and upper ends of their strokes respectively. Fig. 10 is a vertical sectional view, parts being shown in elevation, illustrating another possible modification of the invention. Fig. 11 is a vertical sectional view, showing another possible modification. Fig. 12 is a plan view, partly in section of another modification. Fig. 13 is a vertical central section of the pulsator 70 shown in Fig. 12.

Referring to the drawings in detail and particularly to Fig. 1, the invention is here shown as applied to a cow milking machine. The numeral 1 designates the milk pail on 75 which fits the tight cover 2. The pulsator 3 is preferably mounted on the cover. While the invention may be employed in connection with systems utilizing a pressure greater than atmospheric, in the present instance 80 the invention is shown as adopted to a system of the vacuum type. A vacuum main is shown at 4 to which the pulsator is connected by a flexible pipe 5 which is attached to a nipple 6 at the end of the suction pipe 7. 85 A branch pipe 8, which also forms the casing of a check valve, leads to an opening in the milk pail cover 2. The lower end of the branch pipe 8 is received within a recess 9 in a bushing 10, which is mounted in a hole 90 in the cover, this bushing also forming a valve seat 11 for a check valve 12. The check valve is preferably in the form of a cylindrical rod suitably shaped at its lower end to engage the valve seat and preferably 95 guided by sliding in an opening in a bushing 13. The valve being of the same diameter throughout, is very easy to construct and it may be put in place or removed by simply sliding it through the bushing 13. It is 100 retained in its chamber by the cap 14.

When suction is applied through the pipe 5, the check valve is raised and the air exhausted from the interior of the pail. Air is also drawn from the pulsator through the 105 pipe 7. In the present construction, the invention is illustrated as utilized in connection with teat cups of the two-chambered type, although obviously the invention is not limited in this respect. The teat cups shown 110

are of the character set forth in United States Letters Patent No. 1,146,584 and comprise an outer casing 16 and a flexible inner lining or inflation 17. The inner chambers 5 which receive the cow's teats are connected by means of the branches 18 of the claw or manifold 19 with the milk pipe 20, which discharges through the milk cock 21 directly into the milk pail. It will be seen that as the 10 air is continuously exhausted from the interior of the milk pail through the branch pipe 8, constant suction will be applied through the pipe 20 to the inner chambers of the teat cups. The outer chambers, or 15 spaces between the inflations 17 and casings 16, are connected through the branches 22 of the claw and the pipe 23 with one of the nipples 24 of the pulsator. Through the action 20 of the pulsator, to be described, conditions of partial vacuum and atmospheric 25 pressures are caused alternately to exist in the outer chambers. In the construction illustrated, the pulsator is shown as provided with two nipples 24, so that two sets 30 of teat cups may be operated at one time, but it is obvious that this is not essential. The operations of milking as performed by an apparatus of this character are well understood and need not be discussed in detail. Briefly, it may be stated that the 35 continuous suction in the inner chambers of the cups draws the milk from the teats, while the intermittent suction and atmospheric pressure in the outer chambers results in the 40 collapsing of the lining so as to compress or massage and relieve the teat, preventing congestion thereof and continuous drain upon or injury to the cow. It is important that the pulsating action be regular and capable of adjustment.

Taking up now the pulsator itself, with which the present invention is particularly concerned, this comprises a casing 30, which is provided at its lower end with a flange 31, 45 which rests upon a seat 32 on the milking machine cover, the flange being secured to the seat in any suitable manner as by means of the screws 33. In Figs. 1 to 5 the casing is shown as a built-up construction comprising a drawn metal shell 34 with a core 35 forced tightly therewith. This construction possesses many advantages from a manufacturing point of view as the shells can be readily and cheaply formed by a press while 50 the cores are easily produced in an automatic screw machine. Manifestly the casing may be made in any other suitable way, however, for instance as an integral die-casting, as shown at 30^a in Figs. 8 and 9 and 30^b in 55 Fig. 11. A chamber 36 is formed in the lower end of the casing and in this chamber is mounted a flexible diaphragm 37 preferably formed of spring steel or other durable and resilient material. The diaphragm is secured in place in any suitable 60

manner, for instance by having its margin 38 clamped between the flange 31 and the seat 32, a yielding packing ring 39 being introduced if desired. The diaphragm is preferably so shaped that the central part 70 arches downwardly, as indicated at 40 in Fig. 2, the diaphragm being shown as inversely cupped, so as to stand above the seat 32, and as being provided with annular corrugations 41, which tend to increase its 75 flexibility and resiliency. Atmospheric pressure is at all times admitted to the space 42 below the diaphragm, channels 43 in the seat 32, being provided for the purpose. The casing 30 is hollow and has in its lower 80 end a screw threaded bore or chamber 45 which receives a correspondingly threaded plug 46. Mounted to reciprocate in a hole in this plug is a plunger 47, which is provided with an intermediate flange or shoulder 48 and which is formed above the shoulder into a portion of reduced diameter 49, constituting a valve stem, which extends up through the casing.

Above the bore 45 is a suction chamber 50 90 into which opens the suction pipe 7 through which the air is continuously exhausted from the chamber. Above the suction chamber is another chamber 51 into which lead the nipples 24, the passages 52 communicating with these nipples being preferably arranged as shown in Fig. 5, so as to enlarge the chamber 51 and permit free communication to the nipples. It will be seen that the axes of the passages 52 do not pass 100 through the center of the opening in the casing but to either side thereof. In the top of the casing is a chamber 53 which is open to the atmosphere. There are openings between the chambers 50 and 51 and, 51 and 53, valve seats 54 and 55 being formed around these openings, respectively. A passageway is also provided between the chamber 51 and the chamber 36 above the diaphragm, this passageway being shown as 110 comprising a hole 56 extending from the chamber 51 into a vertical bore 57, which is internally screw-threaded at the upper end and reduced in diameter at the lower end, so as to provide a valve seat 58, the bore 115 communicating at its lower end with the chamber 36. In this bore screws an adjusting screw or needle valve 59 having a cone-shaped end 60 adapted to coöperate with the seat 58 and which is bent over at the upper end, as indicated at 61, or otherwise suitably shaped, so as to be readily turned to adjust the amount of opening between the end 60 and the seat 58. The adjusting screw 120 may advantageously be sprung slightly out of a straight line so as to give it a very slight curvature, which will cause it to bind in the screw-threaded bore, this having the effect of maintaining the screw 125 in its adjusted position.

Communication between the chamber 51 and the suction chamber 50 is controlled by a suction valve 65 slidably mounted on the valve stem 49. This valve is supported in 5 its position on the valve stem and is actuated by a spring 66, which rests on the collar 48. The normal or untensioned length of the spring is such that when the diaphragm and valve stem are in normal position as shown in Fig. 2, the valve 65 will 10 be supported on the upper end of the spring slightly below the seat 54.

Communication between the chamber 51 and the chamber 53 is controlled by an air 15 valve 67 adapted to seat on the valve seat 55 and which is provided with a recess 68 which receives the upper end of the valve stem 49. This recess 68 is of such depth that when the valve stem is in the position 20 shown in Fig. 2, a clearance is allowed between the end of the valve stem and the end wall of the recess. A removable cap 69 is preferably fitted in the end of the chamber 53 to prevent the valve 67 from dropping 25 out if the device is inverted, and perforated to permit air to enter the chamber 53. Preferably the construction is such that the rate of flow of air into the chamber may be adjusted so as to modify the squeezing action 30 of the teat cups, as will be more fully explained hereafter. The construction shown for this purpose consists in pivoting a perforated valve disk 70 on the top. By turning the disk on the cap the perforations 35 71 in the disk may be brought into more or less complete registration with the perforations 72 in the cap, so as to regulate the size of the openings through which the air may enter.

40 Considering now the operation of the pulsator, the parts will normally stand in the position indicated in Fig. 2. The diaphragm is formed so as to normally occupy the shape here shown. If the air be now exhausted through the pipe 7 from the chamber 50, it will be seen that owing to the valve 65 being open the air will also be exhausted from the chamber 51, nipples 24 and the connections therewith to the outer 45 chambers of the teat cups. This will cause the teat cup lining 17 to be drawn into the outward or open position indicated in Fig. 1. The air will also be exhausted through the passageway 56, 57 from the space 36 above the diaphragm, the exhaustion of the last-named space taking place gradually owing to the small opening between the valve 60 and its seat 58. The time required 50 to exhaust the chamber 36 to the necessary degree may be nicely determined by adjusting the valve.

As a condition of atmospheric pressure exists in the space 41 beneath the diaphragm, it will be seen that the diaphragm will be 55 quickly subjected to unequal pressures on its

lower and upper surfaces, the pressure below the diaphragm being the greater. Owing to the stiffness of the diaphragm, however, and to its downwardly arched shape, it will not immediately yield to this unbalanced pressure but will maintain its shape until the pressure below it exceeds the pressure above it sufficiently to overcome its initial resistance to bending. As soon as this resistance has been overcome, however, it 70 will immediately collapse or reverse its curvature to the full extent of its upward movement. This will be true because the resistance of the diaphragm to flexure is the greatest when it is downwardly arched, 75 as shown in Fig. 2 and decreases as soon as it is forced out of this arched shape. Furthermore, the movement of the diaphragm is comparatively small, so that the sudden slight decrease in the volume of the chamber 36 caused by the upward movement of the diaphragm is not enough to cause the pressure to build up in this chamber to an extent sufficient to prevent the full upward movement of the diaphragm. In other 80 words, the diaphragm when it moves will not move up gradually as the air is slowly sucked out past the valve 60 but will vibrate quickly or shift over quickly through its full range of movement. This result follows 85 because by the time the reduction of the pressure in the chamber 36 has reached a sufficient degree to overcome the initial resistance to flexure of the diaphragm, this reduction of pressure is more than sufficient 90 to carry the diaphragm through the remainder of its range of movement during 95 which the resistance to flexure is less.

As the diaphragm moves up, it carries 100 with it the plunger 47 and the valve stem 105 49. The first effect of this movement is to cause the collar 48 to lift the spring 66 and with it the valve 65 so as to close the latter, as shown in Fig. 3. Owing to the clearance 110 space between the end of the valve stem and the end of the recess in the valve 67, the valve 65 will close before the valve 67 opens. The condition shown in Fig. 3, is, however, but an instantaneous one as the diaphragm passes immediately into its extreme 115 upper position, as shown in Fig. 4. The further upward movement of the plunger and valve stem, which now takes place, causes the spring 66 to be compressed, thus holding the valve 65 firmly against its seat, 120 and the end of the valve stem is also brought into engagement with the end of the recess in the valve 67 and so lifts the latter away from its seat. The chamber 51 is now cut off from the suction and air rushes in 125 through the holes in the cap 69 and under the valve 67 breaking the vacuum in the chamber 51 and outer chambers of the teat cups. As the suction is still applied to the inner chambers of the teat cups, the linings 130

of the latter are collapsed, having the action already referred to. The air admitted to the chamber 51 also passes down through the passageway 56, 57 into the space 36, thus 5 equalizing the pressure above and below the diaphragm and permitting the latter to spring back to its normal position shown in Fig. 2. This will, of course, permit the plunger and valve stem to return to the 10 position of Fig. 2, under the influence of gravity and of the spring 66, which will permit the valve 65 to open and the valve 67 to close and the operation above described to be repeated. Thus a continuous pulsating 15 or reciprocating movement of the plunger and valve stem is produced and a regular pulsation of pressure in the teat cups is established. The operations will continue as long as suction is applied and the rate at 20 which the pulsations will take place may be adjusted through a wide range by simply turning the screw 59 to open or close more or less the passageway leading to the chamber 36.

25 The action of the construction described is particularly well adapted to the requirements of a milking machine pulsator as the operation of the valve is practically instantaneous and no time is wasted in the change 30 from the condition of suction or release of external pressure in the teat cup in which the milk is drawn from the teat and the condition of pressure or squeeze upon the teat. This permits both of these periods to be of 35 the greatest possible duration in proportion to the number of pulsations per minute, which makes for efficiency and permits the maximum rate of flow of milk to be obtained while providing adequate relief to 40 the teats and so avoiding injury to the cow. It is most always desirable to have the release of the squeeze upon the teat as quick as possible as no advantage is gained by relieving the pressure gradually. In some 45 cases, however, it is not desirable to apply pressure to the teat too quickly and the construction described provides for the adjustment of the rate of pressure, whereby the compression may be made as gradual as is 50 desired. This is accomplished by adjusting the disk 70 on the cap 69 so as to partly close the air inlets. As has been explained, the squeeze caused by the collapsing of the 55 teat cup linings is produced by admitting air at atmospheric pressure to the outer chambers of the teat cups, while the suction continues to be applied to the inner chambers. As the air admitted for this purpose enters through the holes in the cap, the retardation 60 of this air supply will evidently make the squeeze gradual.

The puppet valve construction set forth possesses certain advantages in mode of operation over prior constructions employed 65 as milking machine pulsator valves or for other purposes and it is also exceedingly efficient from the point of view of durability which adapts it particularly to use in situations where it is subjected to steady and continuous action. The latter result follows from the fact that the movement of the various parts is slight and from the further fact that the valves seat and unseat by a movement toward and from their seats instead of by a sliding movement as in 70 most prior milking machine pulsator valves. The chief advantage in the principle of operation referred to resides in the fact that the suction of valve 65 closes before the air inlet valve 67 opens and vice 75 versa, so that there is never a continuous open passage from the atmosphere to the suction chamber or source of vacuum. In this way, no direct leakage of air can take place tending to reduce the vacuum and 80 throwing an additional burden on the vacuum producing instrumentalities.

85 While the embodiment of the invention above described is the one which I now prefer as the simplest and most efficient for the 90 purpose for which it is intended, my invention is not limited thereto but the principle thereof may be carried out in various ways. In Figs. 8 and 9, for instance, I have illustrated a modification of the invention in 95 which I employ a piston reciprocating in a cylinder in place of the flexible diaphragm. In accordance with this construction, the pulsator casing 30* is formed at its lower end into a cylinder 80 in which reciprocates a piston 81 affixed to an extension 82 of the plunger 47. Atmospheric pressure is at all times admitted through a port 43 to the space below the piston. Opening into the cylinder above the piston is a passage 100 56, 57 controlled by an adjusting screw 59, as above described. The pulsator casing contains the valves 65 and 67 and associated parts which operate in the same manner as the corresponding parts shown in Figs. 2, 105 3 and 4. The piston is caused to move upward when the air is exhausted from the cylinder through the passage 56, 57 and is returned to its lower position by a spring 110 83 when the pressure is equalized by the entrance of air through the opened valve 67. In order to prevent the piston from starting upward before the air has been sufficiently exhausted from above it, means are provided 115 for interposing an initial resistance to its movement, corresponding with the resistance provided by the resilient diaphragm in the first form of the invention. In the construction illustrated in Figs. 8 and 9, this resistance is provided by means of balls 84 120 mounted in chambers 85 in the cylinder wall and urged against the piston by springs 86. The piston is provided with shallow recesses 87 which receive the balls when the piston is 125 in its initial or lowest position, as shown in 130

Fig. 8. The balls keep the piston from moving until the exhaustion of air above the piston has continued to a considerable degree, whereupon the pressure beneath the 5 piston becomes so great that the balls are forced back into their chambers and the piston moves quickly up to the position shown in Fig. 9. The operation of the remaining parts of the apparatus is as already 10 described.

In Fig. 10, I have illustrated how the novel puppet valve construction set forth may be employed in connection with an operating or reciprocating device of a different 15 character, from those above described. For purposes of illustration, I have shown these valves as applied to a vacuum operated reciprocating mechanism of the character shown in the patent of Macartney, No. 20 1,270,429, June 25, 1918, for pulsator for milking machines. This reciprocating mechanism is really nothing but a simple form of vacuum motor and comprises briefly 25 a piston 90, working in a cylinder 91 and having a piston rod 92 which actuates the valve stem 49 carrying the valves 65 and 67. A passageway 93, shown in dotted lines, leads from a port 94 in the lower part of the cylinder to a port 95 in a valve seat on the 30 side of the casing. Another passageway 96 leads from the upper end of the cylinder to a second port 97 in the valve seat. A third passage 98 leads from the passage 57, which is connected by a passage 56^a to the suction 35 chamber 50, this passage 98 terminating in a third port 99 in the valve seat located between the ports 95 and 97. The port 99 is thus constantly in communication with the source of vacuum. An oscillating valve 100 40 is pivoted at 101, so as to slide back and forth over the valve seat and is provided in its inner face with a recess (not shown) of the form described in said Macartney patent, which is arranged to place the port 99 45 alternately in communication with the ports 95 and 97, that one of the last-named ports which at any time is not in communication with the port 99 being open to the atmosphere. In the position of the parts 50 shown in Fig. 9, the valve 100 is covering the ports 95 and 99, so as to establish communication between them, while the port 97 is open to the atmosphere. The effect of this is to exhaust the air through the passage 98, port 99, recess in the valve, port 55 95 and passage 93 from below the piston while air at atmospheric pressure enters the port 97 and passes through the passage 96 into the cylinder above the piston. In other 60 words, with the parts in the position shown, the piston is about to start on its downward movement.

In order to reverse the position of the valve 100 so as to cause the piston to reciprocate, movement is transmitted from the

piston rod 92 to the valve by means of a pin 102 which is mounted in the rod and projects through a slot in the wall of the casing, the end of this pin working in a slot 103 in a lever 104. The latter is operatively connected with the valve 100 by means of a plunger 105 pivoted to the valve at 106 and the outer end of which extends through a hole in the lever. A spring 107 is mounted on this plunger and transmits a yielding 70 pressure from the lever to the plunger and valve. A link 108 pivoted to the casing at 75 109 is swung back and forth through a small angle about its pivot by the action of the pin 102 in a cam slot 110 in the upper part of the link. The link is provided with a notch 111, which is adapted to engage alternately with the projections 112 on the valve 100, so as to lock the latter against movement until the proper time. When the piston moves 80 down, it will be seen that the pin 102 also moves down carrying with it the lever 104 and the outer end of the plunger 105. This will swing the plunger about the pivot 106 until it passes the dead center, whereupon 85 the spring 107 will cause the plunger to oscillate the valve 100 upwardly, thereby connecting the port 97 with the port 99 and opening the port 95 to the atmosphere. This will reverse conditions in the cylinder and 90 cause the piston to move upwardly. A reciprocating movement will thus be produced as described in the application of Macartney above referred to and this reciprocating movement will actuate the valves 65 and 67, 95 100 so as to cause a pulsated pressure in the teat cups or whatever else is connected to the nipples 24. Obviously the valves 65 and 67 can be reciprocated by the use of any other appropriate mechanism.

In Fig. 11, I have shown another construction embodying certain features of my invention in modified form and illustrating the applicability of the invention to the production of a reciprocatory movement which 105 may be utilized externally of the pulsating device itself. As here illustrated, the pulsator casing 30^b is without any connection to external passages in which vacuum and pressure are to be pulsated. The device is shown 110 as provided with the diaphragm 37 which actuates the plunger 47, the latter carrying a modified form of valve stem 49^a, the upper part of which is reduced in diameter as indicated at 120, so as to provide a shoulder 115 121 above the valve 65. A valve 67^a is employed which performs the functions of the valve 67 heretofore described but which has an opening extending entirely through it, through which the reduced portion 120 of 120 the valve stem projects. The valve 67^a is lifted from its seat by the engagement of the shoulder 121 with its underside. No nipples 24 or other connections from the chamber 51 to any external source are pro- 125 130

vided, but, as before, the chamber 51 communicates with the passageway 56, 57 leading to the chamber 36 above the diaphragm. It will be seen that when suction is applied to 5 the suction pipe 7, the reciprocating action of the diaphragm, plunger, valve stem and valves will take place just as described in connection with Figures 2, 3, and 4. A reciprocating movement of the valve stem extension 120 will thus be produced, which may be employed for any desired purpose.

In Figs. 12 and 13, I have shown another modification of my invention illustrating a construction in which the suction is applied 15 alternately upon opposite sides of the diaphragm so that the latter is forcibly propelled first in one direction and then in the other by the pressure difference upon the opposite faces thereof. In accordance with 20 this construction, it is not necessary to rely upon the use of springs or the resiliency of the diaphragm to move the same in one direction. The construction illustrated also provides for the operation of two sets of 25 teat cups or pairs of teat cups of a single set, alternately. As shown two pulsator casings 30 are arranged end to end, clamping between them the diaphragm 37. Each of the casings contains chambers and passages arranged substantially as in the construction 35 shown in Figs. 2, 3 and 4. Each of the casings also contains a pair of valves 65 and 67 mounted on a valve stem 49 carried by a plunger 47. The two plungers 47 are of such 40 length and so arranged that they normally bear at all times against opposite sides of the diaphragm. The two suction chambers 50 are connected to the vacuum pipe by means of a Y-connection 122. Each of the chambers 51 is connected by means of passages 56 45 and 57 with the base chamber 36 at one side of the diaphragm and opening into each chamber 51 is a nipple 24. The pulsator casings are illustrated as mounted in horizontal position upon supports 123 on the milk pail cover 2. In operation, the parts being in the position shown in Fig. 13, the air will be exhausted from the chamber 50 of the left-hand pulsator and as the left- 50 hand valve 65 is open, the air will be exhausted from the left-hand chamber 51 and through the nipple 24 from the outer chambers of the teat cups connected with said nipple, the air also being exhausted from 55 the left-hand chamber 36, through the passages 56, 57. At the same time, it will be seen that in the right-hand pulsator the valve 65 is closed and the valve 67 opened. The air is thus admitted to the right-hand 60 chamber 51 and to the outer chambers of the teat cups connected with the right-hand nipple 24, so that the teats in those teat cups are subjected to pressure. The air is also permitted to pass through the passages 56,

57 of the right-hand pulsator to the corresponding chamber 36. When this condition has existed for a sufficient length of time depending upon the adjustment of the screws 59, so that the pressure difference between the two chambers 36 has become sufficient to 65 overcome the resistance to movement of the diaphragm, the diaphragm will be forced over to its opposite position, thereby reversing the condition of the valves. With this construction a diaphragm is preferably employed which is so formed that it will tend 70 to occupy either one of two positions of deformation, one of which is illustrated in Fig. 13. Upon sufficient pressure being applied to the diaphragm, it will spring over from 75 right to left and occupy a second position of reverse curvature from the first. By connecting two sets of teat cups to the two nipples 24, it will be seen that the pulsations 80 will occur alternately in the two sets instead of simultaneously as in the construction shown in Figs. 1 to 4, so that the work will be more or less equalized and the effort required of the suction apparatus will be more 85 uniform.

In Figs. 1 and 6, I have shown a handle construction adapted to be attached to a milking machine pulsator, which is strong, attractive in appearance and at the same time exceedingly simple and inexpensive to 90 manufacture. This handle comprises a single strip of sheet metal 125, which is formed by suitable dies, so as to provide a concave hand grip portion 126. Hooks 127, also preferably formed of sheet metal and welded or 95 otherwise suitably attached to the ends of the handle, are provided for supporting the claws and teat cups when not in use.

From the foregoing description of certain preferred embodiments of my invention, 100 which I have chosen to illustrate the principles thereof and the best mode now known to me of practising the invention, it will be seen that I have invented certain novel principles of construction and operation, which 105 may be usefully embodied in a great variety of structures. It will also be apparent that when expedient, some of the features of the invention may be used without others. I therefore do not wish to be understood as 110 limiting myself to the particular examples of the invention set forth, as various changes and modifications may be made therein within the scope of the appended claims, without departing from the spirit and scope of the 115 invention.

Having thus described my invention I claim:

1. In vacuum operated pulsator mechanism, the combination of a valve for controlling the action of the vacuum and means operated by an unbalanced pressure condition produced by the vacuum for actuating said 120

- valve, said means having an initial resistance to movement greater than its resistance to continued movement after such initial resistance has been overcome.
- 5 2. In a fluid pressure operated pulsator, the combination of valve means for controlling the operating fluid, and means actuated by pressure difference for moving said valve means, said actuating means being constructed to resist without substantial movement any pressure difference less than a pressure difference sufficient to complete the movement of the valve means.
3. In a pulsator, the combination of a diaphragm movable by atmospheric pressure acting upon one side thereof when a predetermined degree of vacuum has been produced on the other side of said diaphragm, said diaphragm normally remaining stationary until such degree of vacuum is reached, and valve means operated by the movement of said diaphragm for controlling the application of the vacuum to the diaphragm.
- 25 4. In a pulsator, the combination of a casing having a motor chamber therein, a fluid pressure operated valve actuating diaphragm in said chamber, said casing having a second chamber therein, valve means actuated by said diaphragm for controlling the connection of said second chamber with a source of vacuum and with the atmosphere respectively, and a fluid pressure connection between said second chamber and said motor chamber.
5. In mechanism of the character described, the combination of a casing, a movable pressure responsive element therein having an initial resistance to movement greater than its resistance to continued movement after said initial resistance has been overcome, means for admitting atmospheric pressure to said casing at one side of said element, a source of vacuum, a connection from the source of vacuum to a space in said casing on the other side of said element and valve means actuated by the movement of said element for connecting said space alternately with the source of vacuum and with the atmosphere.
- 40 6. In fluid operated pulsator mechanism, the combination of valve means for controlling the operating fluid and means for moving said valve means including a flexible resilient metal diaphragm.
7. In fluid operated pulsator mechanism, the combination of valve means for controlling the operating fluid and means for moving said valve means including a flexible resilient metal diaphragm having an initial conformation convex to the direction of application of the operating pressure.
- 45 8. In mechanism of the character described, the combination of a casing having a diaphragm chamber therein, means providing for the admission of atmospheric pressure to said chamber at one side of said diaphragm, said casing having a suction chamber therein adapted to be connected to a source of vacuum, and having an inlet chamber connected with said suction chamber and with the atmosphere respectively, and providing a restricted passage connecting said inlet chamber with said diaphragm chamber at the opposite side of the diaphragm from that subjected to atmospheric pressure, and valve means actuated by the movements of said diaphragm for controlling the connections between said inlet chamber and said suction chamber and between said inlet chamber and the atmosphere.
- 50 9. In a pulsator, the combination of a casing having a diaphragm chamber therein, a flexible diaphragm in said chamber, said casing having a second chamber, valves for controlling the connection of said second chamber alternately with the atmosphere and with a source of vacuum, an operative connection from said diaphragm to said valves for operating the latter, means providing a constantly open air inlet for admitting air at atmosphere pressure to the diaphragm chamber at one side of the diaphragm, a fluid connection from the diaphragm chamber at the other side of the diaphragm to said second chamber, and an adjusting valve for controlling the passage of fluid through said last-named connection.
- 55 10. In a milking machine pulsator, the combination of a casing containing a diaphragm chamber, a suction chamber, an inlet chamber and an air chamber, a flexible diaphragm in the diaphragm chamber, a connection from a source of vacuum to said suction chamber, a connection from the teat cups to said inlet chamber, said air chamber being open to the atmosphere, a connection from said inlet chamber to said diaphragm chamber at one side of the diaphragm, the other side of said diaphragm being subjected at all times to atmospheric pressure, said air chamber, inlet chamber and suction chamber being connected, a valve for controlling the connection between the suction and inlet chambers, a valve for controlling the connection between the inlet and air chambers, and means operated by the movements of said flexible diaphragm for actuating said valves to connect said inlet chamber alternately with said suction chamber and said air chamber.
- 60 11. In a milking machine, the combination of double chambered teat cups, means for connecting the inner chambers of the cups with a source of vacuum, and means for pulsating a vacuum and atmospheric pressure alternately in the outer chambers of the cups, said last-named means including puppet valves and fluid operated actuating means.

therefor, said puppet valves also controlling the action of the fluid on said fluid operated valve actuating means.

12. In a milking machine, the combination of double chambered teat cups, means for creating a suction in the inner chambers of the cups and means for producing alternate pulsations of suction and pressure in the outer chambers of the cups, said last-named means including pulsator valve means and an operating element for said valve means movable by a pressure difference of predetermined value acting upon said element, said element normally remaining stationary until such pressure difference is reached.

13. In a milking machine, the combination of double chambered teat cups, means for exhausting the air from the inner chambers of the cups, a pulsator for controlling the exhaust from or admission of air to the outer chambers of the cups, said pulsator having an air inlet port, and means for controlling the port opening so as to determine the rate at which air shall be admitted to the outer chambers of the teat cups for applying the squeeze to the teats.

14. In a pulsator, the combination of two valve seats, valves adapted to seat on said seats and a movable actuating element for both of said valves, said element having a yielding connection with one valve and a lost-motion connection with the other valve.

15. In a pulsator, the combination of a pair of oppositely facing valve seats, a valve stem, a puppet valve slidably mounted on said valve stem and adapted to seat on one of said seats, a spring carried by said valve stem and engaging said valve, a second puppet valve adapted to seat on the second of said valve seats, and an abutment on said valve stem for engaging said second valve and lifting it from its seat.

16. In a vacuum operated milking machine pulsator, the combination of a casing having a pulsation chamber therein and ports opening into said pulsation chamber, a nipple for the attachment of a pulsation pipe opening into said pulsation chamber,

50 puppet valves for closing said ports, and means for alternately opening and closing said valves, said means acting to close the open valve before opening the closed valve, whereby both of said valves are never simultaneously open.

17. In a pulsator, the combination of a casing having a suction chamber therein, an inlet chamber opening into said suction chamber, and an air chamber opening into said inlet chamber, valve seats surrounding the openings between the suction chamber and inlet chamber, and inlet chamber and air chamber, respectively, a valve stem extending through said chambers, a valve slidably mounted on said stem and adapted to

seat against the seat between said suction chamber and inlet chamber, a spring carried by said valve stem and adapted to engage said valve and move it against its seat, a valve adapted to close upon the seat between said inlet chamber and air chamber, and an abutment on said stem adapted to engage the last-named valve and unseat the same after said first-named valve has been seated by the action of said spring.

18. In a pulsator, the combination of a support, a casing mounted thereon having a chamber at the bottom thereof, and a vertical bore, a diaphragm mounted in said chamber and clamped between said casing and said support, a plunger mounted in said casing carrying a valve stem extending into said bore, the lower end of said plunger engaging said diaphragm, a valve seat dividing said bore into a suction chamber and an inlet chamber, a second valve seat at the upper end of said inlet chamber, puppet valves mounted on said valve stem adapted to engage said seats, and a fluid connection between said inlet chamber and said diaphragm chamber.

19. In a pulsator, the combination of a casing having a chamber in the lower part thereof, and a vertical bore, a diaphragm mounted transversely of said chamber, a plunger mounted in the casing and having a valve stem extending upwardly through said bore, the lower end of said plunger engaging said diaphragm, said bore having a pair of valve seats therein dividing the same into a suction chamber, an inlet chamber and an air chamber, a puppet valve slidably mounted on said valve stem and adapted to seat upwardly against the lower of said valve seats, a spring carried by said plunger for supporting said puppet valve, a second puppet valve slidably mounted on said valve stem and adapted to seat downwardly on the upper of said valve seats, an abutment on said valve stem adapted to engage said upper puppet valve and lift the same from its seat, and a fluid connection between said inlet chamber and said diaphragm chamber.

20. In a milking machine, the combination of a pail lid, a pulsator thereon, a vacuum pipe connected to said pulsator, a check valve housing constituting a connection from the vacuum pipe to an opening in the lid, and a check valve mounted in said housing, said check valve being removable without removal of the vacuum pipe or check valve housing.

21. In a milking machine, the combination of a pail lid, a pulsator mounted thereon, a suction pipe connected with the pulsator, a check valve housing connected with said suction pipe, a bushing mounted in said suction pipe opposite to said check valve housing, and a check valve slidably mounted

in said bushing and adapted to be inserted into or removed from its housing by longitudinal movement through said bushing.

22. In a milking machine, the combination 5 of a pail lid, a pulsator mounted thereon, a vacuum pipe connected with said pulsator, a branch connected with said vacuum pipe and extending from the same to the pail lid, a bushing mounted in said vacuum pipe opposite to the opening in said branch pipe, a check valve seat in the lid at the lower end of said branch pipe, and a check valve slid- 10 ingly mounted in said bushing and adapted to seat on said valve seat.

23. In a milking machine, the combination 15 of a pail lid, a pulsator mounted thereon, said pail lid having an opening through it, a bushing mounted in said opening and having a port therethrough surrounded by a 20 valve seat and having a recess in its upper side around said valve seat, a horizontally disposed vacuum pipe projecting from said pulsator above said pail lid, a branch pipe connected to said vacuum pipe and extend- 25 ing substantially at right angles to the same toward said pail lid, the end of said branch pipe being received in the recess in the bushing in the pail lid, and a vertically movable check valve within said branch pipe adapted 30 to seat on the valve seat in said bushing.

24. In a milking machine, the combination 35 of a pail lid, having a seat for a pulsator thereon and a seat for a check valve housing, a pulsator having a suction pipe projecting therefrom carrying a check valve 40 housing, and means for securing said pulsator to its seat on the pail lid, the lower end of said check valve housing being held in engagement with its seat by reason of its connection with the suction pipe and the pulsator.

25. In a milking machine, the combination 45 of a pail lid, a bushing therein having a seat for a check valve housing and a seat for the check valve, a pulsator mounted on the pail lid, a suction pipe projecting from the pulsator, a check valve housing carried by the suction pipe and adapted to seat at its lower end on its seat in the pail 50 lid bushing, a check valve in said housing adapted to seat on the check valve seat in the pail lid bushing, an opening in the suction pipe opposite to the check valve housing through which the check valve may be in- 55 serted or removed without disturbing the suction pipe or check valve housing, and means for closing said opening.

26. In a milking machine, the combination 60 of a milk pail and a lid thereon having a seat on top thereof, a pulsator casing secured to said seat, a flexible metal dia- 65 phragm clamped between the lower end of said casing and said seat, said casing having a chamber in the lower end thereof in which said diaphragm is contained, and having a

suction chamber, an inlet chamber and an air chamber therein, said inlet chamber being connected with said suction chamber and said air chamber, a nipple connected with said inlet chamber, an adjustable air inlet 70 for admitting atmospheric air to said air chamber, a passage-way connecting said inlet chamber with the chamber in the base of said casing above the diaphragm, a valve for controlling the passage of fluid through 75 said passage-way, a vertically movable plunger mounted in said casing and adapted to rest upon and be operated by said dia- phragm, a valve stem carried by said plunger, valves on said valve stem for controlling 80 the openings between said inlet chamber and said suction chamber and air chamber respectively, a vacuum pipe connected to said suction chamber, a branch connecting said vacuum pipe with the interior of the 85 milk pail and a check valve in said branch.

27. In a fluid pressure operated pulsator the combination of valve means for controlling the operating fluid and means for moving said valve means including a flexi- 90 ble resilient diaphragm of sufficient stiffness to normally maintain a given initial con- formation and to return to such conforma- 95 tion after flexure.

28. In vacuum operated pulsator mecha- 95 nism the combination of valve means for controlling the action of the vacuum, means forming a chamber adapted to be intermitt- ently connected with the source of vacuum, a valve actuating motor element in said 100 chamber having an initial resistance to movement and adapted to be moved by a predetermined pressure difference produced by the exhaustion of said chamber, the volume of said chamber being sufficient as com- 105 pared with the movement of said motor ele- ment to permit the latter to move to the limit of its stroke without restoring the pressure equilibrium thereon when the movement of said element is once initiated 110 by the attainment of the predetermined pres- sure difference.

29. In a fluid pressure operated pulsator, the combination of valve means for controlling the operating fluid and actuating 115 devices therefor, capable of actuation in one direction by a pressure difference, said actuating devices being constructed to pro- vide an initial resistance to movement in said direction greater than the resistance to 120 movement after such initial resistance has been overcome and to return to initial posi- tion upon the decrease of the pressure difference.

30. In a fluid pressure operated pulsator, 125 the combination of valve means for controlling the operating fluid, an actuating dia- phragm therefor and means for creat- ing an unbalanced pressure condition upon opposite sides of said diaphragm prior to 130

the movement thereof sufficient to complete the movement of the diaphragm when such movement is once initiated, said diaphragm having a tendency to resume its initial position as soon as said unbalanced pressure condition is destroyed.

31. In a fluid pressure operated pulsator, the combination of valve means for controlling the operating fluid, and means actuated by pressure differences for controlling the operation of said valve means, said actuating means being constructed to resist movement until a predetermined pressure difference is attained and then to move instantly 15 from one of its operative positions to the other thereof.

32. In a fluid pressure operated pulsator, the combination of a resilient diaphragm normally flexed in one direction and adapted 20 to be flexed in the opposite direction when the pressure upon the opposite sides thereof is unbalanced, and valve means adapted to be actuated by said diaphragm only upon reversal of the flexure thereof.

33. In a fluid pressure operated pulsator, the combination of a motor element, a valve stem adapted to be actuated thereby, and lift valves carried by said valve stem, said stem having a yielding connection with one 30 of said valves and having a non-yielding lost motion connection with the other of said valves.

34. In a fluid pressure operated pulsator the combination of a motor element, two 35 valve seats, lift valves adapted to seat on said seats and a valve stem adapted to be actuated by said motor element, said valve stem passing through an opening in one of said valves and having a yielding connection therewith and having a lost motion 40 connection with the other valve.

35. In a pulsator, the combination of an actuating diaphragm, a valve stem adapted to be actuated thereby, and a plurality of 45 puppet valves carried by said valve stem, one of said valves having a yielding connection with said valve stem and the other of said valves having a non-yielding lost motion connection with said valve stem.

36. A milking machine pulsator, including a casing having an air inlet chamber therein, a perforated cover for said inlet chamber, a pulsation chamber in said casing, a nipple for the attachment of a pulsation 55 pipe opening into said pulsation chamber, a port between the air inlet chamber and pulsation chamber, a valve seat around said port, said casing also having a suction chamber therein, a port between said pulsation 60 and suction chambers, a valve seat around said port, puppet valves adapted to seat on said respective valve seats, and motor means within said casing for alternately opening and closing said valves.

37. A milking machine pulsator including

a casing having a pulsation chamber therein, a port for admitting air to said pulsation chamber, a puppet valve for governing the admission of air to said chamber through said port, said valve having a recess therein, 70 a valve stem fitting loosely in said recess, and means for reciprocating said valve stem to actuate said valve so as to alternately open and close said port.

38. A milking machine pulsator including 75 a casing having an air inlet chamber therein, and a pulsation chamber below said inlet chamber, a nipple for the attachment of a pulsation pipe opening into said pulsation chamber, a port between said air chamber and pulsation chamber, the bottom of the air inlet chamber around said port forming a substantially horizontal valve seat, a cap-like puppet valve adapted to seat on said valve seat and having a recess in its 80 underside, a substantially vertically mounted valve stem, the upper end of which projects into said recess, and motor means for reciprocating said valve stem to actuate said valve so as to cause the valve to alternately 85 be lifted from or permitted to seat upon said valve seat.

39. A milking machine pulsator including 90 a casing, having a pulsation chamber therein and a suction chamber below said pulsation chamber, said casing having a port 95 therein connecting said suction and pulsation chambers, a puppet valve for closing said port, a substantially vertical valve stem upon which said valve is mounted and 100 motor means for reciprocating said valve stem to cause said valve to alternately open and close said port.

40. A milking machine pulsator including 105 a casing having a motor chamber therein, a motor element in said chamber, a pulsation chamber formed in said casing, said casing having a port opening into said pulsation chamber, a puppet valve for closing said port, and a reciprocating valve stem 110 for actuating said valve, said stem extending into the motor chamber and adapted to be reciprocated by engagement with said motor element.

41. A milking machine pulsator including 115 a casing having a motor chamber therein, a motor member movable in said casing, said casing having a suction chamber therein above said motor chamber, and having a pulsation chamber above said suction chamber and having a port connecting said suction and pulsation chambers, a substantially 120 vertical valve stem mounted for up and down reciprocation and having its lower end extending into said motor chamber, said valve stem extending upwardly through said suction chamber and said port, and a puppet valve carried by said stem and adapted to be actuated by the movement thereof, 125 so as to alternately open and close said port. 130

42. A milking machine pulsator including a casing having a pulsation chamber therein, a wall of said chamber having a port opening therein and being formed to provide a substantially horizontal valve seat, a puppet valve adapted to seat against said seat, a substantially vertical valve stem loosely engaging said valve for actuating the same, and means for reciprocating said valve stem.

43. A milking machine pulsator including a casing having a pulsation chamber therein, the casing wall above said chamber having an inlet port opening into said

chamber and providing a substantially horizontal valve seat surrounding the upper end of said port, a puppet valve having an annular portion adapted to seat on said valve seat, and having a central boss having a recess opening from the underside thereof, and a vertical reciprocable valve stem, the upper end of which is adapted to be loosely received in said recess, whereby when said valve stem is raised, it will lift said valve from its seat, and when lowered will permit said valve to firmly close upon its seat.

HERBERT McCORNACK.
